APPARATUS FOR PRODUCING PRINTING PLATES

Milton C. Taylor, Chicago, Ill., assignor to Partridge & Anderson Company, Chicago, Ill., a corporation of Illinois

Application June 1, 1938, Serial No. 211,241

9 Claims. (Cl. 153—2)

This invention relates to appliances for use in conjunction with small portable printing machines or such as use a peripherally grooved cylinder, segmental or cylindrical bed plate for holding type, electroplates, etched rubber or other cuts for printing.

In printing from cuts or electroplates produced from a matrix, the cut, such as rubber, is vulcanized or otherwise secured on a metallic plate of zinc or other material, which may be tinned, or holder of a curvature to fit the segment, drum or cylinder usually adapted to revolve against the suitable inking apparatus, roller or ribbon in order to produce an impression upon the sheet to be printed, and the same are held on the drum or bed plate by means of clamps commonly used to hold type, or by means of type groove engaging members soldered to the bottom or inside of the electroplate. It is essential that the lines of printing, or cuts, be squared across the paper or printed sheet, and much difficulty has been experienced in this connection, not only because of the apparent defects in the methods heretofore practiced, but also due to the inability of properly clamping and holding the plate and the practical difficulties in getting a soldered groove engaging member line up with the type or advertising matter appearing on the cuts so that the latter will be squared across a sheet, and because such methods are impractical, cumbersome and expensive.

The present invention, therefore, has for a primary object the production of a new article of manufacture or novel plate, and method and apparatus of producing same, together with holding means therefor, whereby the ends and sides of the plate will be properly squared, and the type or advertising matter appearing on the cuts accurately lined up with the drum or cylinder grooves and the printed matter squared or properly lined up across a sheet, instead of relying upon the haphazard or guesswork method heretofore employed, such as severing the ends of the plate without squaring the same as by merely cutting the ends at right angles to the sides without reference to the lines of type or matter on the cut mounted on the plate, or squaring said ends by guesswork and without being sure that the same are parallel or otherwise properly arranged with respect to the type, print matter or designs of the cuts, thus resulting in the lines of printing or cuts being distorted or extended at a tangent and therefore defective, as will be

well understood by a person acquainted with the art.

Further objects are to facilitate shearing and squaring of the ends of the plate and cut, and subsequently the printing produced therefrom; to provide a novel plate and holding means therefore in cooperation with the type receiving grooves of the drum, so that the plates and cuts will be accurately and firmly held and may be arranged in juxtaposition or abutting relation in a common groove, so that one or more of the plates bearing advertising or printed matter may be mounted upon the same drum; to provide a gauge for setting the plate and insuring that in the severing or cutting of the ends of the plate in the shearing operation performed by the apparatus or machine, will be squared with the design or printing lines of the cut and parallel thereto so that when the cut is mounted on the cylinder, the lines of the printing will be parallel with the axis of the cylinder and with the ends of the printed sheet, and to provide novel method and means for bending or forming the ends of the plate to frictionally engage the type grooves and positively hold the plate or cut in any desired position of mounting on the cylinder or drum to facilitate such formation and also the printing throughout the production of innumerable copies.

30 A still further object is to provide a novel method and apparatus for squaring the ends of the plate of the cut with the lines of type or other matter depicted thereon, in which the latter serve as guides or aligning means, and which uses a gauge with grooves exactly corresponding to the grooves of the segment or drum of the printing machine, and in which a section of such drum or cylinder may be so employed together with means to hold the plate in properly gauged position for cutting and formation of holding means, which frictionally engage the type grooves or slots of the cylinder in the printing machine and greatly facilitates placing and removing and changing of the plates or cuts, and insures proper location thereof on the printed sheets.

40 45 50 A still further object is to provide novel means for shearing the ends of the plate to square the same with the printed matter and to simplify the formation of the plate for mounting and retaining the same on the cylinder or drum of the printing machine.

Other objects and advantages will appear and be brought out more fully in the following speci-

fication, reference being had to the accompanying drawings, wherein:

Fig. 1 is a front elevation showing the apparatus for performing the shearing and bending or forming operations on the plates, the same being shown in battery form;

Fig. 2 is a front elevation, partly in section, taken along the line 2—2 of Fig. 3 in back of the gauging segment, the upper part of the machine being omitted;

Fig. 3 is a side elevation of the apparatus taken on the line 3—3 as shown in Fig. 1;

Fig. 4 is an enlarged fragmentary central vertical sectional view taken on the line 4—4 of Fig. 1, and showing the shearing operation completed;

Fig. 5 is an enlarged fragmentary vertical sectional view taken on the line 5—5 of Fig. 1;

Fig. 6 is a plan view of an electroplate before the same is sheared off at the ends for squaring the same;

Fig. 7 is a view similar to Fig. 6 with one end sheared off to square the same;

Fig. 8 is a sectional elevation taken on the line 8—8 of Fig. 1;

Fig. 9 is a central vertical sectional view corresponding to Fig. 4 but taken on the line 9—9 of Fig. 1 and showing the first step in the bending or forming operation;

Fig. 10 is a view similar to Fig. 9 but showing the subsequent step in the forming or bending operation;

Fig. 11 is an enlarged horizontal sectional elevation taken on the line 11—11 of Fig. 9;

Fig. 12 is an enlarged fragmentary vertical sectional elevation taken on the line 12—12 of Figs. 9 and 11;

Fig. 13 is a plan view of the bottom forming die;

Fig. 14 is a fragmentary perspective view of a portion of the completed plate or product showing the manner of bending the same;

Fig. 15 is an enlarged fragmentary vertical sectional view taken on the line 15—15 of Figs. 3 and 8;

Fig. 16 is a fragmentary elevation of a cylinder, segment or drum with a plate mounted thereon;

Fig. 17 is an enlarged fragmentary sectional view of a portion of the segment of the printing machine with two plates mounted thereon in abutting relation or juxtaposition;

Fig. 18 is an enlarged fragmentary sectional view similar to Fig. 10 showing a modified form of apparatus, the same being taken on the line 18—18 of Fig. 19;

Fig. 19 is an enlarged horizontal sectional elevation corresponding to Fig. 11 and taken on the line 19—19 of Fig. 18;

Fig. 20 is a view similar to Fig. 12 being a sectional elevation taken on the lines 20—20 of Figs. 18 and 19;

Fig. 21 is a plan view of the lower forming die shown in Figs. 18, 19 and 20;

Fig. 22 is a fragmentary perspective view of the product produced by the apparatus shown in Figs. 18 to 21, inclusive;

Fig. 23 is a fragmentary elevation showing a modified form of product applied to a segment; and

Fig. 24 is a fragmentary vertical sectional view showing the formation of the product disclosed in Fig. 23.

Referring more particularly to the drawings, 25 is a table of a frame suitably adapted to support a bed plate or base 26 having an upright

standard 27 adjustably or otherwise mounted and retained thereon as by bolts 28, the top wall of the bed plate being provided, if desired, with slots 29 to permit the forward and backward adjustment of the standard 27 and the horizontal arm 30 formed at the upper end thereof and provided with a vertical bearing sleeve or guide 31 for a plunger 32 which may be reciprocated vertically in any suitable way. As illustrated, the 10 back of the plunger is formed with a rack bar 33 engaged by a pinion 34 journaled in a bearing sleeve 35 of the arm 30 and adapted to be turned by a hand lever 36 that is oscillated to impart up and down movement to the plunger. Obviously, 15 however, suitable power operated means or motor may be provided for actuating the plunger 32, as will be fully appreciated by anyone acquainted with the art. In addition, removable stop pins 37 and 38 may be provided in sockets of the plunger to limit the upward and downward movements of the plunger, such means being capable of adjustment, if desired. This means is common to both of the units constituting a battery of devices forming the apparatus or machine, as seen in Fig. 1 of the drawings and, consequently, a description of one will suffice.

The machines are interchangeable but as equipped in the manner shown, the device shown at the right of Fig. 1 is equipped for shearing the 30 ends of a plate such as disclosed at 39 in Fig. 6 of the drawings bearing an electroplate or cut 40 which may be produced from rubber or vulcanized material or otherwise secured to the face of the plate, which is of arcuate form and adapted 35 to fit the contour of a segment or drum 41 having T-grooves 42 designed to receive clips or retaining clamps for securing type to the peripheral surface of the printing cylinder in the manner heretofore practiced. It has been customary to secure the type or an electroplate on the surface of the cylinder by means of H-shaped retainers or T-shaped ribs soldered or otherwise secured to the concave side of the plate and across the same. However, such means have been found 40 expensive, impractical and cumbersome and the present invention aims to overcome these disadvantages.

The ends 43 and 43a of the plate shown in Fig. 6 are indicated as extending at a tangent, that is, not square with the sides of the plate 39 and the cut or stencil 40 mounted thereon, but more particularly, not parallel with the ends of the cut, and especially the lines 44 of type or advertising matter appearing upon the cut, and 55 which must extend perfectly square across the sheet printed therefrom. The previous method employed for squaring the ends of the plates was merely haphazard and guesswork, the ends of the plate being severed off by a shearing or cutting device at right angles to the side edges. This gave no assurance that the printed matter would be squared with the sheet or that the lines of type or cut would be squared with or parallel to the type grooves of the drum since the cutting was left more or less to guesswork and no means provided to shear the ends of the plate parallel to the type lines or advertising matter appearing on the cut or stencil 40 heretofore referred to.

The method, apparatus or machine and product of the present invention are designed to overcome these difficulties, and, in accordance therewith, means is provided to shear off the ends of the plate and to gauge or so position said plate as to shear said ends squarely so that the printed matter will be produced square with the sheet or

paper subsequently printed, and the ends so formed as to properly engage the type grooves or slots of the segment or drum of the printing machine, said ends being so spaced apart as to accurately correspond with the spacing of the 5 grooves of the segment which will be spanned by the plate when in position on the printing machine and being controlled or engaged by segments corresponding exactly with the segment or drum of the printing machine as well as permitting the plate to be set accurately not only for the shearing operation, but also for the bending and forming operation to produce novel means to engage the type grooves and for retaining the plates firmly in position when so engaged.

Referring more particularly to the form of the invention illustrated in Figs. 1-16, inclusive, the shearing operation is shown more particularly in Figs. 3 and 4, while the bending and forming operation is shown more particularly in Figs. 8-14, inclusive. However, having more particular reference to Figs. 1, 3, 5, 8 and 15, relative to the bearing 31 or vertical guide sleeve for the plunger 32, it should be noted that the front of the bearing or sleeve has a removable plate secured by 10 fastening means 45 extending through openings in the plate and open faced sleeve, suitable 15 threaded openings 46 being provided for receiving the stud bolts or screws, or other suitable 20 fastening means being provided for the purpose. 25 The bearing is provided with suitable means of lubrication and the pinion 34 is inserted at the open side of the sleeve and provided with bearings 47 on each side which receive the pivot 48 having a reduced portion 49 and a collar 50 held by 30 a pin or stud screw securing the parts in assembled relation. Any suitable form of mounting for the handle or lever 36 may also be provided.

The lower end of the plunger 32 has a casting 35 51 removably bolted thereto through the medium of its vertical portion illustrated as shown at 52 in front elevation, as seen particularly at the right hand side of Fig. 1 and also in Figs. 3 and 4. The bottom part 53 of the casting extends horizontally beneath the lower end of the plunger 32 and is held by a stud bolt 54 while a horizontal web or apertured flange 55 extends forwardly and entirely across the front of the unit of the battery constituting the machine or element thereof set up for the shearing operation. The block 53 extends below the horizontal supporting flange 55 and provides a bottom seat 56 for shearing blade or die 57 secured therein by means of stud bolts 58 which extend horizontally through and engage threaded apertures in the block 53 in staggered relation to the fastening means 54. The bottom or cutting edge 59 of the cutting blade or die 57 is inclined, as seen especially in Fig. 1, and the ends thereof are protected by the depending guide extension 60 at the ends of the block in spaced relation to the ends of the blade and adapted to travel over the ends of the lower plate 61, the upper edge of which is beveled in the opposite direction to the bevel 59 of the blade 57. A horizontal guide member or plate 63 is mounted on a plurality of stud bolts 64 passed through unthreaded apertures in the plate or flange 55, the threaded lower ends of the bolts being anchored in the plate 63 as by engaging threaded apertures thereof, and compression springs 65 are fitted in coacting recesses in the opposed faces of the plates 55 and 63 respectively, namely the bottom face of the plate 55 and the upper face of the plate 63, as shown at 66 and 67 respectively. The plate 63

fits against the upper blade 57 of the shearing device and is adapted to have movement relative thereto during the shearing operation when the blade is lowered and raised with the plunger 32 manually or by power in the manner heretofore described.

The plate 63 acts as a pressure plate and has a bottom projection or rib 68 cooperating with a corresponding rib 69 at the top of a plate 70 bolted to a block 71 as at 72 and block 71 is recessed as at 73 to receive a transverse pressure plate 74 which projects above the top of the block and receives the lower cutting blade 61 between it and the pressure plate 70, the bottom wall 75 supporting the plates 61, 70 and 74 in position, relatively. When so adjusted, the bolt 72 is used to clamp the blade in position. The front of the base 26 is recessed to receive a bed plate or block 16 having apertures 77 registering with corresponding apertures of the block 71 to receive dowel pins 78 in order to properly align the blocks, after which they are connected by stud bolts 79.

It will be noted from Figs. 3 and 4 that the plates 26 and 76 project forwardly relative to the shearing blades and are designed to support a gauge in the form of a segment 80, which is or corresponds to the half-segment of a portion of the drum or cylinder 41 which constitutes a part of the printing machine having the T-grooves designed to receive the type and to hold the plates for printing purposes.

As seen in Fig. 2, the end plates of the segment 80 are anchored as at 81 and are held between the lower extensions 76 and the side arms 50 of a U-shaped gauge member 82 connected by a cross member 83 at the front and bottom edges of the arms, as indicated at 84. Pivots or stud bolts 85 extend through the extensions 76 and the side plates of the segment 80 and pivotally support the U-shaped gauge 82 which may be swung in an arc over the peripheral surface of the segment 80 and held in adjusted position by frictional engagement of the hub of a wheel 86 threaded on the reduced end portion 87 of the pivot 85. A plate 88 extends transversely of the segment 80 which, by reason of its construction, may be considered a calibrated gauge, and said plate 88 is pivoted between the sides of the U-shaped member, as indicated at 89 and has its edge portion turned inwardly to form a contact edge 90. This plate is operable by a handle 91 and is normally held in engaging position by a spring 92, shown in the form of a flat leaf spring secured to the bottom of the plate 88, and having its free end contacting with the top of the connection 34, as especially seen in Fig. 3 of the drawings so as to hold the edge 90 against the segment or the lines of type 44 impressed upon the rubber or other type plate or stencil 40 mounted upon the plate 39.

The adjustment may be effected by swinging the U-shaped gauge member after raising the plate 88 by the handle 91 against the action of the spring 92 after first releasing the pressure 65 frictionally holding the gauge member by the wheel 86 and then clamping the same, after which the gauge plate 88 is allowed to return against the spaced lines of type under the action of the spring 92. As before stated, the end 70 plates of the segment 80 are held between the extensions 76 and the arms 82 and the hand wheel 86 is, in reality, an enlarged flanged nut, while a nut 93 is engaged on the threaded end of the opposite or spaced pivot for the U-shaped gauge member. Thus, a plate 39, as shown in

Fig. 6, in order to shear off the ends thereof squarely with the line of type, is placed upon the segment so that one of the ends 43 will project over the plate or anvil 70, as shown in dotted lines in Fig. 3 so that said end 43 will project between the shearing blades 57 and 70. By loosening the hand wheel or nut 86, the gauge member 82 may be set in any desired position over the segment and this is done in order to bring the edge 90 against certain of the type lines 44 on the plate or cut 40 to square the plate with said lines. When this is done, the hand wheel or nut 86 is tightened to frictionally clamp the U-shaped member in adjusted position in which the type lines serve as calibrations. Of course, the handle 91 is pressed down against the stop pin 89a to raise the plate 88 and cause the edge 90 thereof to press against the cut 40 so that the plate 39 is retained in position. The handle 36 is then actuated to lower the plunger 32 and cause the upper or movable shearing blade 57 cooperating with the lower shearing blade 70 to shear off the end of the plate 39 as shown in Fig. 4 of the drawings so that said end will be parallel to the type lines. This operation is repeated on the opposite end of the plate 39, when the plate is ready to be formed for engagement with the type grooves of the segment or drum of the printing machine. However, it may be mentioned that in shearing the ends of the plate 39, the type grooves of the segment 80, inasmuch as they correspond with the grooves 42 of the segment or drum 41 of the printing machine, will be so set or calibrated that the ends of the plate 39, when formed to engage the grooves 42, will be spaced apart exactly as are the spaces between the respective grooves 42 to be engaged thereby, as shown in Fig. 16 and as will now be described.

The second unit of the machine or battery of elements, as disclosed in Fig. 1, is the same as that shown at the right hand portion of Fig. 1 and as heretofore described and is connected thereto by a horizontal gusset plate or web 94, which is of arcuate formation and set upon a true arc with respect to the pivots 87 as an axis. This gusset plate is provided with a slot 95 through which the adjacent arm of the U-shaped gauge member 82 is movable.

In lieu of the plate 51 and parts carrying the shearing blade and movable pressure plate and anvil 63 against said blade as described in connection with Figs. 3 and 4, a block or head 96 is mounted on the lower end of the plunger 32, being retained in position as by means of stud bolts 97. This block carries a cross head 98 retained in position by stud bolts 99 and formed at the front with parts 55a, 56a, 63a, 64a, 65a, 66a, 67a and 68a, corresponding to the parts shown and described in connection with Figs. 3 and 4 and identified by the same number except for the supplementary reference character *a*. The cross head 98 is recessed at the back to receive a plate 100 and at the front to receive a die plate 101 held in position by horizontal stud bolts 102 extending through corresponding apertures in the reduced portions of the cross head 98.

A spring block 103 is positioned between the plates and beneath the reduced portion of the cross head and the lower edge of the plate 101 is provided with recesses 104 accommodating the heads of stop pins 105 set in sockets in the block 103. The lower edge of the plate 100 is

provided with recesses 106 and the block 103 with sockets 107 receiving compression springs 108 engaging guide pins 109 at the back. These guide pins are carried by lugs 110 projecting upwardly from a horizontally movable die plate 111 which operates beneath and against the aligned lower edges of the plates 100 and 101 and the block 103. The forward and top edge of the die plate 111 is provided with a series of recesses 112 and this plate is movable upon a supporting plate or block 113 carried upon the bed plate of the machine. The forward edge of the block 113 is recessed as at 114 to receive a die block 115, which is held in position by stud bolts 116 and the upper edge thereof is formed with an inward projection or rib 117, and said edge is designed to receive the advertising plate 39 after the ends have been sheared off in the manner previously described and as shown in Fig. 7 of the drawings.

A segment 80a corresponding to the segment 80, previously described, is mounted at the front in horizontal alignment with the segment 80 and with the grooves thereof in alignment so that after the plate is sheared off, it may be simply moved across the gusset plate or web 94 onto the gauge member produced by the segment 80a and will be maintained in the same position relative to the forming dies, as it was with respect to the shearing dies or blades. Also, any suitable means may be provided on the segment 80a to gauge and hold the plate 39 in any desired or adjusted position. Incidentally, it may be noted that the pins 105 also serve as stop pins for the plate 39 when disposed in position over the forming die 115, as clearly shown in Fig. 8 of the drawings when the die 101 is elevated by actuating handle 36 to raise the plunger. By actuating the handle in the opposite direction, the plunger is lowered to cause the die 115 to engage the projecting edge of the plate 39, which initially is in rectilinear form, although the plate is curved later to fit the periphery of the segment. This will cause said edge to be directed downwardly as indicated at 118 in Fig. 9 of the drawings, being bent against and below the rib 117.

The die 111 is then adapted to be actuated to move it forwardly against the bent portion 118 and, by reason of the recesses 112, certain portions of the bent portion 118 will be bent or curved inwardly, as shown at 119 and the intermediate portions will be formed into tongues directed downwardly so as to properly and frictionally engage the walls of the grooves 42 of the printing machine segment in the manner clearly disclosed in Figs. 16 and 17 of the drawings and thereby hold the printing plate in accurate position on the segment or drum of the printing machine for the purposes heretofore explained.

In order to move the die 111 forwardly from its rearward position shown in Fig. 9 to the forming position shown in Fig. 10 against the action of the springs 108, a substantially U-shaped frame 120 is provided at the back of the machine somewhat corresponding to the frame at the front, as shown more particularly in Fig. 11. This frame has its side portions mounted in recesses 121 in the supporting plate or block 113 and provides journals for a transverse shaft 122 provided with cams 123 designed to engage the vertical rear portions or lugs 110 of the die plate 111. These parts are retained in position by stud bolts 124 and the shaft is adapted to be turned by a handle 125 or other suitable man-

ual or power operated means to oscillate the shaft and cams for moving the die 111 into a projected or retracted position assisted by the springs 108. When both ends of the printing plate have been formed in the manner described and particularly as shown in the resultant product disclosed in Fig. 14 of the drawings, the printing plate may be slid into the grooves of the segment or drum of the printing machine, as shown in Fig. 16, and this will insure that the printed matter will be absolutely squared on the sheet. Thus, a dual function is served in that the shearing insures the formation of the ends of the printing plate to properly engage the drum grooves and the squaring thereof with the printed matter, while the bending provides means for engaging the grooves of the drum so that this relation will be insured in the printed product. Of course, when one end of the printing plate has been formed, the plate is merely reversed in position and moved edgewise to cause the engagement of the bent portions 118 and 119 with the proper groove of the segment 80a so that the opposite unbent edge of the plate will contact with the stop pins or gauge members 105 as is done in the initial bending operation. It may also be mentioned that the sides of the U-shaped member 120, which support the ends of the shaft 122, also serve as guide means for the die block 111, and the vertically movable plates 100 and 101, as will be clearly apparent from Figs. 11 and 12 of the drawings.

In Figs. 19 to 22 of the drawings, a modification is shown in which the structure is the same as that shown and described in connection with Figs. 1 and 8 to 14, inclusive, except that instead of moving the die 111 forwardly to produce the inwardly bent tongues 119, the die is moved rearwardly to form outwardly bent tongues 126. For this purpose, the die 127 corresponding to the die 111 is normally held forwardly by springs 128 set in recesses 129 in the block 113 and act against lugs or ribs 130. The top forward portion of the die 127 is provided with a recess 131 forming ribs or lugs 132 against which the portion 118 is bent and the shaft 122 is provided with eccentrics 133 pivotally connected by links 134 or other articulated connection with apertured lugs 135 at the rear edge of the die 127. Thus, by actuating the handle 125, the die 127 is moved rearwardly against the action of the springs 128 to cause the ends of the plate to be bent in the manner shown in Fig. 22 of the drawings. These bent portions 118 and 126 engage the grooves of the printing cylinder or drum in the manner shown in Fig. 23, the portions 126 being directed outwardly instead of inwardly to engage beneath the adjacent T-members forming the grooves of the cylinder to frictionally hold the printing plate in position instead of beneath the T-members engaged by the portions 118 as shown in Fig. 17. Otherwise, the construction is substantially the same as that already described. It may also be mentioned that while the handles or levers 36 are mounted at the right hand side of each unit of the machine or apparatus, the handle or lever 125 is conveniently mounted at the left hand side so as to greatly facilitate the operation, especially in view of the fact that the hand wheel or nut 86 is at the right hand side corresponding to the position of the handle 36 thereabove and, therefore, facilitates movement in unison in clamping the printed plate and in shearing off the ends of the same.

In Fig. 24 of the drawings, a fragmentary part of the machine is shown for producing a slightly modified formation at the ends of the printing plate in which, after the end is bent down as at 118, a portion of said downwardly bent end is directed horizontally or outwardly as indicated at 136 and upwardly at an acute angle slightly less than a right angle with the portion 118. In this instance, the die 137 has the bottom edge formed with a series of upwardly and rearwardly inclined recesses 138 and the bottom die 139 is raised at corresponding rib portions 140 to correspond with the recesses 138, which are stamped up to frictionally engage beneath the T-members of the grooves of the drum by forming one continuous member instead of being severed as between the portions 118 and 126 in the manner shown and described in connection with Figs. 18 to 21, inclusive, and the product formed thereby, as shown in Fig. 22. It is also to be understood that in each instance, the shearing step is employed prior to the formation of the ends and that these steps can be successively carried out with accuracy and dispatch, thereby greatly simplifying the production and reducing the cost of the manufacture of the printing plate over the cumbersome and expensive methods heretofore in vogue and absolutely insure that the various objects heretofore pointed out will be effected.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to secure by Letters Patent is:

1. In a forming machine of the class described, coacting dies and an anvil, the dies and anvil being designed to receive the work therebetween, a curved gauge member positioned to receive the work thereon at its periphery and comprising an arcuate supporting portion, a U-shaped member enveloping said gauge, means for clamping said U-shaped member in different angular positions over the arcuate portion, and means carried by said U-shaped member to set against the printing matter of a plate to cause the coacting dies and an anvil of the machine to act on the plate parallel to the printed matter thereon.
2. In an apparatus of the class described, a frame, a gauge member on the frame, an anvil, a vertically reciprocating upper die formed to coact with the anvil and bend down the edges of a printing plate in parallel relation to type matter thereon, and a forwardly and rearwardly movable lower die member cooperating with the anvil to form the bent down edge into straight and angulated tongues with portions extending normal thereto whereby the tongues at opposite ends of the plate are disposed in opposite directions.
3. In an apparatus of the class described, a frame, a gauge member on the frame, an anvil, a vertically reciprocating upper die formed to coact with the anvil and bend down the edges of a printing plate in parallel relation to type matter thereon, a horizontally slideable lower die member cooperating with the anvil to form the bent down edge into straight and angulated tongues with portions extending normal relative thereto whereby the tongues at opposite ends of

the plate are disposed in opposite directions, said die member being cushioned and held in one direction, means forming a stop for one end of the plate and means for actuating the lower die member.

4. In a forming machine for producing curved printing plates for printing machines using a peripherally grooved cylinder, forming means designed to receive the work therebetween, a gauge member positioned to receive the work thereon at its periphery and comprising an arcuate supporting member having peripheral longitudinal grooves, a U-shaped member enveloping said gauge and including forwardly extending spaced parallel arms, and a horizontal transverse bar disposed in spaced parallel relation to the arcuate supporting member to support a curved printing plate thereon, means for clamping said U-shaped member in different angular positions over the arcuate supporting member and means carried by said U-shaped member to act as a gauging member in connection with printed matter on the arcuate plate for setting the plate in a position in which the forming means will act on the plate parallel to the type or print matter on the plate and normal to the plate.

5. In an apparatus for producing curved printing plates for mimeograph machines, a frame, a convex arcuate gauge member on the frame and disposed on an arc of a true circle, an anvil, a vertically reciprocating upper die formed to bend the ends of a printing plate in parallel relation to type matter thereon, a horizontally movable lower die member cooperating with the anvil to produce tongues in parallel relation to the type matter and formed with portions to bend said tongues substantially at right angles in opposite directions at opposite ends of the plate, said die member being cushioned and held in one direction, means forming a stop for one end of the plate, and means for actuating the lower die member.

6. The combination with a metal treating machine of the class described having co-acting die members, a substantially semi-cylindrical gauge member having spaced parallel longitudinal grooves in its periphery for receiving tongues bent from a curved printing plate and constituting a holding means therefor during the treating operation, a U-shaped member pivotally

10 mounted to swing over the gauge member, means to hold the U-shaped member in adjusted position and a gauge plate pivoted to the U-shaped member and having an inwardly directed edge portion normally held toward the gauge member to contact one end of the printing plate, lines of type or print matter thereon to square the tongues with the ends of the printing plate and print matter or lines of type on the plate or cut

15 thereof.

7. An apparatus for producing arcuate printing plates comprising spaced metal sheet treating members and spaced gauging elements located beneath said members, said gauging elements 20 having type grooves in horizontal registry and projecting laterally thereof respectively whereby the plates may be slid from one element to the other free of resetting and while maintaining the ends of the plates parallel to the printed matter thereon.

8. An apparatus for producing arcuate printing plates comprising spaced metal treating and forming members, a gauging element having a plurality of spaced segments located beneath 25 said members and connected by a depressed gusset plate of corresponding arcuate segmental formation and set upon a true arc with respect to the axes of the segments whereby a printing plate may be slid from one segment to the other 30 in either direction for positioning the same beneath the treating and forming members or removed laterally therefrom, a U-shaped gauge swingable over the peripheral surface of each segment and frictional means to hold the gauges 35 in adjusted position.

9. An apparatus for producing arcuate printing plates comprising spaced metal treating and forming members, spaced gauging elements located beneath said members, said gauging elements having type grooves in horizontal registry and projecting laterally thereof respectively whereby the plates may be slid from one element to the other free of resetting and while maintaining the ends of the plates parallel to the printed matter thereon, a U-shaped gauge swingable over the peripheral surface of each element and frictional means to hold the gauges in adjusted position.

MILTON C. TAYLOR.
